UNITED STATES PATENT OFFICE.

ALEXANDER F. WARD, OF DETROIT, MICHIGAN.

PILL-MACHINE.

SPECIFICATION forming part of Letters Patent No. 311,620, dated February 3, 1885.

Application filed May 15, 1884. (No model.)

To all whom it may concern.

Be it known that I, ALEXANDER F. WARD, of Detroit, in the county of Wayne and State of Michigan, have invented new and useful 5 Improvements in Pill-Machines; and I do hereby declare that the following is a full, clear, and exact description thereof, reference being had to the accompanying drawings, which form a part of this specification.

10 This invention relates to certain new and useful improvements in machines for the manufacture of spherically-shaped pills; and the invention consists in the peculiar construction of parts, their combination, and arrangement, 15 by means of which the mass from which the pills are made, having been first put into the form of a pencil or pipe by the ordinary process, is rolled into pills by a peculiar motion given to a part of the mechanism, by means 20 of which the pills in passing through are rolled with a change of axis, whereby they are spherical in form when completed; or, in other words, the motion by which the axis is changed has a near resemblance to the motion of the 25 two hands in rolling an irregularly-shaped mass into a ball.

Figure 1 is a top plan view of my improved machine, showing the rotating wheel and concave in their relative positions when in operation. Fig. 2 is a like view with the rotating wheel and concave removed. Fig. 3 is a side elevation. Fig. 4 is a horizontal vertical section on the line $x-x$ in Fig. 2. Fig. 5 is an enlarged horizontal vertical section on the line 35 $y-y$ in Fig. 2. Fig. 6 is a detached perspective of the concave. Fig. 7 is a diagram showing the manner in which the axis of the pills is changed in the grooves or corrugations of the rotating wheel and concave, whereby a 40 spherical shape is given to such pill.

In the accompanying drawings, which form a part of this specification, A forms a bed and standard, which supports the working parts. B is a yoke or bail, in the two ends of which 45 is journaled a corrugated wheel, C, and this bail at or near its rear end is journaled at D to the supporting-standard in such manner that when in operation the corrugated wheel is in the position shown in Figs. 1, 3, and 5, 50 and when not in operation is thrown backward, as shown in Fig. 4, the bail rotating

upon its trunnions or bearings to allow this to be done for ease in cleaning the wheel and other parts when required. Motion is given to this corrugated wheel by means of a pinion, E, belt F, wheel G, and carried upon one of the trunnions D, which trunnion also carries the tooth-pinion H, which engages with the gear-wheel I, rigidly secured to the shaft which carries the corrugated wheel. The 60 open ends of the yoke B are provided with ears B', which, when the wheel is in the position shown in Fig. 1, rest upon the top of the standard portion of the frame A, and each of these ears is provided with a set-screw, a, by 65 means of which this end of the yoke carrying the corrugated wheel or roller may be elevated or depressed, as the size of the pills being made may require.

J is a yoke the free ends of which are loosely journaled upon short shafts b, projecting outwardly from either side of the standard portion of the frame, and so constructed and journaled that said yoke may have a lateral motion upon its bearings. This yoke carries 75 a corrugated concave, K, so arranged and secured by set-screws c that its corrugations are made coincident to the corrugations of the rotating wheel C.

A shaft, L, is suitably journaled across the 80 front of the bed, and this shaft is provided with a crank, M, upon which is sleeved a box, N, which, when the parts are in place, has a reciprocating motion between the jaws O, which project from the rear face of the concave K, as very clearly shown in Fig. 5. Upon this shaft there is also an eccentric, P, which is partially embraced by a yoke, Q, such yoke consisting of two arms projecting from the rock-shaft R, one of such arms embracing the upper and the other the lower portion of such eccentric, while the rock-shaft R is journaled longitudinally, as shown in Figs. 2 and 4, by means of screw-points S, which pass through lugs T, cast upon the bed 90 and center, and support the rock-shaft. Secured upon the upper side of this rock-shaft is a lug, U, the free end of which engages between two lugs, W, also cast upon or secured to the rear face of the concave. This lug U 100 may be cast with the rock-shaft or made separate from it and secured to it in any known way,

although, preferably, I tap it into such rock-shaft, as shown in Fig. 4.

A pulley is secured upon the shaft L, and a belt running to any convenient source of power 5 gives motion to the various working parts of the device.

In practice the mass from which the pills are to be made is rolled into pencils or pipe in the ordinary manner, and cut off at a suitable length to correspond to the width of the corrugated wheel and concave. These pencils are fed by the operator into the flaring part or mouth of the concave. The rotation of the shaft L through the box N gives a vertical vibrating and partially-rotating motion to the concave, so that the mass, under the operation of such motion, with the rotation of the corrugated wheel, is cut into sections, one for each of the corrugations, the whole being adjusted for the size of pills required to be made. Now, if this were all, the pills would not be round, but oblong with rounded ends, their axis being coincident to the axis of the rotating wheel but by means 25 of the eccentric P upon the shaft L and its connections, as described, a lateral motion is given to the yoke carrying the concave, by means of which each separate mass of material is compelled to change its axis at each rotation of the shaft completely at right angles to the axis it had before the rotation commenced, and this is continued with each succeeding pencil fed to the machine, and the result is perfectly-formed spherical pills, my object in this construction being to perform the operation in very much the same manner that it would be performed by human hands rolling an irregular mass into a ball.

The axis of the corrugated wheel or roll 40 when the device is in operation is coincident with that of the journal-bearings of the yoke which carries the concave. The oscillating and vibratory motion, as well as the lateral motion of such concave obtained by its connections with the main driving-shaft, should be about fifteen to eighteen of such motions to one revolution of the roll, or somewhat in this proportion, depending upon the size of such roll to a certain extent, and the difference, as 45 such roll is driven from such main driving-shaft, is obtained by the intervening gear.

As shown in Fig. 7, the corrugations of the concave and the roll are coincident when in their normal position, and the chamber thus 55 formed between each pair of these corrugations is not perfectly round, as the axis, laterally, is longer than the vertical axis, giving such chambers more the form of a somewhat flattened circle. This form is necessary, so 60 that in the lateral vibrations of the concave it will change the axis of the sections of the mass under treatment with every successive vibration, and as shown in Fig. 7.

What I claim as my invention is—

1. In a pill-machine, the combination of a 65 corrugated wheel or roll rotated with a continuous feed with a corrugated concave having an oscillating and laterally-vibrating motion upon an axis coincident with that of the roll, substantially as and for the purposes described. 70

2. In a pill-machine, a corrugated wheel or roll journalized in a yoke which in turn is journalized to the main frame, substantially as specified. 75

3. In a pill-machine, a concave having an oscillating and laterally-vibrating motion, and forming a hopper to receive the mass in pencil form to be operated, in combination with a corrugated wheel or roll, substantially as 80 and for the purposes set forth.

4. In a pill-machine, a yoke one end of which is journalized to the frame and having a corrugated wheel or roll journalized between its free ends which is rotated by suitable connections with a main driving-shaft and adapted to be thrown back into the position shown in Fig. 3, as and for the purposes described. 85

5. In a pill-machine, and as a means for giving the concave its oscillating motions, and in combination with the main shaft, a crank in said shaft having a box sleeved thereon and engaging with and between parallel jaws projecting from the rear face of said concave, substantially as specified. 90

6. In a pill-machine, and as a means for giving the concave a laterally-vibrating motion, and in combination with the main shaft, an eccentric on said shaft engaging with a pair of parallel arms secured to a rock-shaft, the latter being provided with a spur or lug which engages with a lug or lugs projecting from the rear face of said concave, substantially as set forth. 95

7. In a pill-machine, and in combination with a suitable frame, a main driving-shaft having a crank and an eccentric, each engaging with the concave through the intervening mechanism herein described for the purpose of giving such concave an oscillating and lateral vibrating motion, substantially as described. 105

8. In a pill-machine, a corrugated concave supported by a yoke having an oscillating and lateral vibrating motion, and adjusting set-screws, in combination with a corrugated wheel or roll having a continuous rotary motion, substantially as and for the purposes described. 110
